PACKAGED PRODUCT AND CLOSURE
THEREFOR

Willis J. Pippert, Ridlonville, Maine

Application May 21, 1935, Serial No. 22,501

7 Claims. (Cl. 229—65)

This invention relates to the packaging of loose bulk materials such as coffee, in ground or bean form, flour, and other grain, granular and pulverized materials as are usually purchased by the housewife in small quantities.

The object of the invention is to securely put up such materials in package form of a definite weight or quantity, securely sealed against sifting out of the contents as a package is handled, permitting ready access to the packaged contents and the reclosing or resealing of the package as the contents are withdrawn in small quantities for consumption.

Such products as coffee, in bean and ground form, put up in pound paper bags, have been in the market for sale to housewives and have been sold in large quantities. Heretofore, such packages have been closed with a tying member consisting of a flat, narrow piece of readily bendable metal, having thereon a paper covering, which tying member was attached below the mouth of the bag, either by clinching the tying member through a wall of the bag, or by first attaching the tying member to a strip of paper and then pasting the strip of paper across the bag near the mouth thereof. The ends of the metal strip of such tying members extend beyond the side edges of the bag and, after the bag has been filled with a given quantity of material, the mouth end of the bag is repeatedly rolled or folded over the tying member and the extending ends of the tying member are then folded over the body of the bag. The bags had to be made of extra length in order to provide a place of attachment for the tying member and to provide material for the repeated rolling or folding operations. These operations were primarily performed by hand and produced, on the whole, a very unsatisfactory package. It was necessary for the housewife, in order to keep the package sealed, to roll down the bag as the material was withdrawn, or else empty the contents of the bag into a separate container.

The present invention eliminates the many objectionable features to the previous practice, and results in many advantages, which will appear from the following specification.

In the accompanying drawing, Fig. 1 is a perspective view of a closed package with the closure member being slid to closing position; Fig. 2 is a perspective view of a folded duplex paper bag; Fig. 3 is a side elevation of the closure member; Fig. 4 is a bottom view of the closure member; Fig. 5 is a perspective view of a package with the closure member in position in connection with

a bag, part of the contents of which has been withdrawn; Fig. 6 is an enlarged fragmentary end view of the upper portion of the bag and closure member; and Figs. 7 and 8 are similar to Fig. 6, showing modified forms of the invention.

This invention, for the purpose of illustration, is shown and described in use with a duplex paper bag. The container 1 comprises an outer bag body 2, consisting of the bottom 3, the side walls 4, and the end walls 5. The bag body 2, is provided with a lining 6, which is coextensive with the bottom, side and end walls of the body. The bag body is creased at 7, in order that the bottom 3 of the bag may be folded flat against the body thereof and the end walls 5 are provided with creases 8, in order that the end walls may be folded inwardly, which creases permit folding of the entire bag in a flat condition, as shown in Fig. 2, whereby the bags may be stacked in quantities for bundling and shipment. The bag is preferably made with a rectangular bottom of greater length than its width, in order that the bag, when filled, will stand upright.

The bag, of the type shown in Fig. 2, having an outer body and a coextensive inner lining, is filled with a predetermined, weighed or measured amount of a loose bulk material and the portions of the end walls 5, above the level of the contents of the container, are then tucked inwardly, as shown in Fig. 1, and the mouth end of the bag is then folded over to form an upstanding flange 9, a fold 10, and a downwardly extending lip 11. The fold 10, if desired, may be previously scored, as indicated at 12, in Fig. 2, for convenience in closing the filled package. In the type of duplex bag shown in Fig. 2, the upstanding flange 9, the fold 10, and the lip 11, when folded as shown in Fig. 1, will consist, at the outer edges, of eight thicknesses of paper, and at the central portion, of four thicknesses of paper, which can readily be understood from an examination of Fig. 2, by noting the folding of the paper in creasing along the line 12. The eight thicknesses of folded paper, at both marginal edges of the package, provide substantial thickness and result in the fold 10 taking a bead-like formation 13, as shown in Fig. 6. The folding allowance, necessary to constitute the flange 9, the fold 10, and the lip 11, need not exceed one inch, that allowance being ample to obtain a satisfactory sift-proof closure and permitting the lip 11 and the mouth edge 14 of the bag, to lie flat against the flange 9, without folding or distorting the edge 14 of the bag mouth, either during the folding operation or the subsequent handling

of the package. It has been found satisfactory to make but a single fold forming the lip 11, but such lip 11 may be given a double fold, if desired.

The package, when thus filled, with its end 5 closed as explained, is provided with a closure member 15, which is made of sheet metal, preferably sheet tin or sheet steel, bent preferably to the form shown in Figs. 3, 4, and 6, and comprising a curved back member 16, having a pair 10 of wings 17, formed by bending the lateral edges of the closure member inwardly and upwardly. The faces of the edges 18 of the wings, consequently lie in intersecting planes. The wings 17 are preferably spaced apart a distance less than 15 the combined thickness of the outer edges of the flange 9 and lip 11, defining a slot 24 between them.

The distance apart of the edges 18 is dependent 20 upon the thickness of the folds 9 and 11. It has been found that if these edges 18 normally touch or are too close together, it is not practical to slide the closure member into position over the folds and to remove it by sliding motion. For 25 these reasons, it is recommended that the distance apart of the edges 18 be regulated in the construction of the closure member so as to produce a lengthwise slot 24 between said edges, which is slightly less in width than the combined thickness of the flange 9 and lip 11. There is a slight 30 spring action to the closure member when made of metal, tending to force the edges 18 securely against the folds. In order to more conveniently introduce the folds into the closure member, the closure member is slightly cut away at its under 35 ends, as shown in Fig. 4.

The closure member is slidably secured to the folded end of the container by introducing one 40 end of the fold between the wings 17 and then sliding the closure member completely over the fold 10 and against the flange 9 and the lip 11. It is preferred to have the edges 18 of the wings 17 so closely together that they will compress the flange 9 and the lip 11 at the line of engagement and in instances where this relation is exceedingly close, the edges 18 may tend to cut 45 slightly into the outer sheet of the flange 9 and the lip 11. The fold 10 fits within the channel 19 and will assume a more or less loose character, somewhat in the form of a bead 13, comprised wholly of material of the bag body and 50 lining. The bead-like formation 13 is thicker than the thickness of the flange 9 and the lip 11 underneath the edges 18 of the wings 17 and in consequence, the extra bead thickness tends to 55 assist in holding the closure member firmly in position against upward strain or pull on the closure during handling or carrying of the package.

The user of the contents of the package can 60 readily slide the closure retaining member from the closure end of the package and it will be found that the edge 14 of the mouth of the bag has not been deformed or creased but, on the contrary, remaining in substantially the flat condition in which it comes off the bag machine. The contents of the bag may consequently readily 65 flow from the bag in order that a desired amount of the contents may be withdrawn. As the level of the material in the bag falls, by reason of withdrawal of part of the contents, the container may be folded along a new line, such as 25, in Fig. 5, just above the new contents level, and the closure member may be again slid into securing position in the same manner as it was initially 70 applied to the container.

The invention has been disclosed in connection with a duplex bag, but it is equally applicable to containers of but a single thickness of material, which may have their open mouths folded down once, or, if desired, a double fold may be made in the lip by folding the loose end of the lip, preferably inwardly on the under side of the lip 11, so that it may, if desired, pass also into the slot 24.

A different type of fold is shown in Fig. 7, 10 which may be desirable for use in some instances. The fold shown in Fig. 7 is preferably made by scoring the mouth end of the container at 20, 21 and 22, and then folding along these lines, with the fold 21 depressed with respect to the 15 folds 20 and 22. In this instance, the closure retaining member 15 is slid into position in the same manner as heretofore described.

A modification of the type of closure member is shown in Fig. 8, in which the closure retaining 20 member is substantially circular in cross-section and the edges 23 lie in substantially the same plane, but otherwise the use of the closure member is the same as described.

I claim:

1. A package comprising a duplex paper bag having an outer paper body and an inner paper lining, said lining being substantially coextensive with the body, said body and lining forming a bottom, side walls, end walls and a closure portion, said container being adapted to hold a predetermined amount of loose material, said closure portion having an upstanding flange, a fold and a downwardly extending lip said flange and lip being in surface engagement, a closure retaining member slidably arranged to hold said flange and lip together, said closure retaining member comprising a back, spaced wings extending inwardly and upwardly, oppositely positioned retaining edges on said wings, said edges engaging said lip and said flange at a distance below said fold and pressing said lip and flange together along the line of contact of said edges with said portions of said flange and lip.

2. A package comprising a duplex paper bag 45 having an outer paper body and an inner paper lining, said lining being substantially coextensive with the body, said body and lining forming a bottom, side walls, end walls and a closure portion, said end walls being foldable inwardly between the side walls, said container being adapted to hold a predetermined amount of loose material, said closure portion having an upstanding flange, a fold and a downwardly extending lip said flange and lip being in surface engagement, 50 the folds of said end walls being extended substantially to the level of the upper surface of the material contained in said package and folded inwardly between the side walls and extending in folded condition into said flange, fold and lip, 55 providing multiple thickness of material at the marginal portions of said flange, fold and lip, a closure retaining member slidably arranged to hold said flange and lip together, said closure retaining member comprising a back, spaced wings 60 extending inwardly and upwardly, edges on said wings, said edges engaging said lip and said flange at a distance below said fold and pressing said lip and flange together along the line of contact of said edges with said portions of said flange 65 and lip.

3. A package comprising a container having a substantially flat bottom, side and end walls, said walls being made of flexible and readily foldable material, said container being adapted to hold a 70

predetermined weighed quantity of loose material, the portion of said container above the level of the upper surface of said material being folded to provide an upstanding flange, a fold and a downwardly projecting lip said flange and lip being in surface engagement, a closure retaining member engaging said flange and lip and freely slideable in a direction parallel to said fold, said closure retaining member comprising a section 5 of sheet metal having its side edges bent inwardly toward each other, providing a continuous space within said closure member, said edges being spaced apart a distance less than the combined thickness of said upstanding flange and lip, 10 said flange and lip being positioned between the aligned edges of the closure retaining member and being held together in close engagement along the line of contact of said closure member with said portions of said flange and lip, one 15 edge of said closure retaining member pressing against said lip and the other edge pressing against said flange, said fold and the upper portions of said upstanding flange and lip, extending into said continuous space within said closure 20 member, said container being adapted to be folded at succeeding levels of the said loose material, as material is withdrawn from said container, and said closure member being adapted to so 25 slidably fit over each of such successive folds.

30 4. A package containing a loose material, such as coffee, comprising an outer body and an inner lining, having a bottom, sides and ends, said body and lining being made wholly of paper and readily foldable by hand over the entire surface 35 of said body and lining from the bottom thereof to and including the mouth thereof, said container being adapted to hold a weighed amount of coffee, the upper portion of the body and lining being folded above the upper surface level of the 40 coffee to form an upstanding flange, a loose fold and a downwardly projecting lip said flange and lip being in surface engagement, a closure retaining member formed of sheet metal, said closure retaining member having its ends bent 45 downwardly to form a back and continuous, substantially aligned edges, the distance apart of said edges being less than the thickness of said flange and lip, said flange and lip being positioned between the aligned edges of the closure 50 retaining member and being held together in close engagement along the line of contact of said closure member with said portions of said flange and lip the said edges of said closure retaining member compressing the said flange and 55 said lip inwardly at the base of said loose fold, and sealing the container against the escape of the contents thereof, said loose fold lying within the space formed by the back and downwardly bent edges of said closure retaining member, said 60 closure retaining member being retained in position solely by contact with said flange and lip and being removable to permit removal of part of said coffee, by sliding it lengthwise of said flange and lip, said body and lining being foldable crosswise of the container at any level 65 formed by the coffee after removal of part thereof, to again form a flange, loose fold and lip, and said closure member being adapted to slide over said last mentioned flange, fold and lip, in the same manner as herein described.

70 5. A package containing a loose material such as coffee, comprising an outer body, and an inner lining, having a bottom, sides and ends, said

body and lining being made wholly of paper and readily foldable by hand over the entire surface of said body and lining from the bottom thereof to and including the mouth thereof, the upper portion of the body and lining being folded above the 5 upper surface level of the contents thereof to form an upstanding flange, a fold and a downwardly projecting lip, said flange and lip being in surface engagement, a closure retaining member formed of sheet metal having a back and depending side portions, said back and depending side portions being substantially circular in cross section and forming internally thereof a substantially tubular channel, the edges of the depending side portions being spaced apart and facing 10 each other to form a slot between said facing edges, the width of said slot being slightly less than the thickness of the said flange and lip beneath the said fold, said fold being positioned within said channel and the inside surface of said 15 flange and lip being in surface engagement and positioned in said slot between said facing edges and held together in close engagement along the line of contact of said facing edges with said portions of said flange and lip, said closure member being adapted to slide lengthwise over the outer surfaces of said flange and lip to open and close said package, said body and lining being foldable crosswise of the container at any level 20 formed by the contents thereof after removal of a part thereof to again form a flange, fold and lip, and said closure member being adapted to slide over such last mentioned flange, fold and lip in the same manner as herein described.

6. A closure member for containers adapted to 25 hold loose bulk material, comprising bent sheet metal having a back, downwardly extending portions on each side of the back forming a channel, wings extending inwardly and upwardly with respect to said downwardly extending portions, 40 said wings extending toward said channel and terminating in oppositely positioned free edges facing each other, said wings being disposed angularly with respect to said downwardly extending portions, said edges forming a slot located at the lower portion of said closure member, said slot being of a predetermined width and bordered on each side by the free facing edges of said wings and being adapted to have a portion of a bag-fold threaded thereto, with the 45 said facing edges pressing on opposite sides of said fold to retain the portions of said fold in surface contact.

7. A closure member for containers adapted to hold loose bulk material, comprising bent sheet 50 metal having a back, downwardly extending portions on each side of the back forming a channel, said downwardly extending portions extending inwardly to form the bottom of said channel and terminating in oppositely positioned free 55 edges facing each other, said edges being disposed in an arc with respect to said downwardly extending portions, said edges forming a slot located at the lower portion of said closure member, said slot being of a predetermined width and bordered on each side by the free facing edges of 60 said portions and being adapted to have a portion of a bag-fold threaded thereto, with the said facing edges pressing on opposite sides of said fold to retain the portions of said fold in 65 surface contact, the said closure member being substantially circular in cross section.
